United States Patent Office.

EDWARD DITHRIDGE, OF PITTSBURG, PENNSYLVANIA.

Design No. 2,726, dated August 6, 1867.

DESIGN FOR A LAMP-CHIMNEY.

The Schedule referred to in these Letters Patent and making part of the same.

TO ALL WHOM IT MAY CONCERN:

Be it known that I, EDWARD DITHRIDGE, of Pittsburgh, in the county of Allegheny, and State of Pennsylvania, have originated or designed a new Design for Lamp-Chimney, of which the following is a full, clear, and exact description, reference being had to the drawing accompanying this specification, and forming part thereof, in which—

Figure 1 is an exterior elevation of my improved design for glass lamp-chimneys, and Figure 2 is a section through the line $x\ x$, fig. 1.

My improved design for lamp-chimneys consists in making a number of flutes, $b\ b$, curving outwards, and arranged around the lower part of the glass chimney, extending upwards from the base c , the upper portion a of the chimney being plain.

What I claim as my invention, and desire to secure by Letters Patent, is—
The design for lamp-chimney, hereinbefore set forth and shown.

In testimony whereof I, the said EDWARD DITHRIDGE, have hereunto set my hand.

Witnesses:

W. BAKEWELL,
Jos. A. BUTLER.
